MOUTHPIECE FOR MUSICAL WIND INSTRUMENTS

Filed July 30, 1924

FIG. 1

Fig. 2

FIG. 3

INVENTOR
Paul Arthur
By Nissen & Frank
ATTYS.

UNITED STATES PATENT OFFICE.

PAUL ARTHUR, OF ELKHORN, WISCONSIN, ASSIGNOR TO FRANK HOLTON & CO., OF ELKHORN, WISCONSIN, A CORPORATION OF ILLINOIS.

MOUTHPIECE FOR MUSICAL WIND INSTRUMENTS.

Application filed July 30, 1924. Serial No. 729,028.

This invention relates to mouthpieces for musical wind instruments, such as cornets, trombones, and other instruments of a like nature, in which the vibration is produced by 5 the lips of the musician.

The object of the invention is to provide a mouthpiece which may be operated either as a standard mouthpiece or operated to provide a shock absorbing device for the lips of the 10 musician, and it may also be used as a no pressure device to prevent the operator from exerting undue pressure upon the lips. The various features of the mouthpiece are incorporated within the normal tubing length 15 of the instrument.

The invention is exemplified in the combination and arrangement of parts shown in the accompanying drawing and described in the following specification, and it is more 20 particularly pointed out in the appended claims.

In the drawing—

Fig. 1 is a longitudinal section of an instrument mouthpiece embodying one form of 25 the present invention;

Fig. 2 is a section on line 2—2 of Fig. 1; and

Fig. 3 is a section on line 3—3 of Fig. 1.

The numeral 10 designates the main body 30 portion of the mouthpiece having the usual flared opening 11 at one end thereof and having a cylindrical tube 12 at the opposite end. Telescoping over the tube 12 in a second tube 13 which tapers on its outer periphery to fit 35 the tube of the instrument in the usual manner. The end of the tube 13 opposite the instrument is provided with a flange 14 which carries a cylindrical rim 15 at its outer periphery. The edge of the rim 15 overlaps a 40 shoulder 16 on the mouthpiece body 10, there being a sufficient space 17 to permit the tubes 12 and 13 to move longitudinally on one another. A spring 18 is interposed between the 45 flange 14 and the body 10 to normally force the flange 14 away from the shoulder 16. A pin 19 enters an opening 20 in the shoulder 16 to hold the parts against relative rotation. An outer sleeve 21 is threaded on the mouthpiece body 10 and is provided with a flange 22

which limits the outward movement of the 50 tube 13.

It will be apparent that the spring 18 provides a shock absorbing medium for cushioning the lips against sudden movement of the instrument toward the musician. This protection is of great importance, especially 55 when the musician is playing while riding or marching. It should be noted that the telescoping portions which enclose the spring partially surround the body portion of the 60 mouthpiece and the connecting tube therefore so that it is included within the usual length of the mouthpiece so that the tubular length of the instrument is not increased as would be the case if a special spring attachment 65 were interposed between the mouthpiece and the instrument.

The tubes 12 and 13 are provided with longitudinally aligned openings 23 and 24, respectively, which are offset longitudinally 70 relative to one another when the spring 18 is expanded. A spring 25 surrounds the portion of the tube 13 having the openings 24 therein, the spring being provided with openings 26 which may be brought into registration with the openings 24. The spring may also be turned to move the openings 26 out of registration, thus closing the openings 24. The spring preferably fits the tube 13 sufficiently tight to remain in its various positions of adjustment due to friction between 75 the parts.

It is well known that a great majority of musicians when playing naturally press the instrument more tightly against the lips 85 when playing the higher notes. This in time tends to deaden the sensitiveness of the lips and interfere with the technique of the player. A few musicians acquire the ability of playing the higher notes without increasing the pressure on the lips, which method is called the "no pressure" method of playing. This is recognized as being the ideal way of producing the high notes where the musician is able to play in this way. The present invention facilitates this no pressure method 90 for the reason that when the pressure on the lips reaches a predetermined amount the

openings 23 and 24 are brought into registration, thus preventing further sound until the pressure is reduced. Practice with an instrument having this no pressure attachment enables the musician to acquire the no pressure habit of playing so that he not only improves the quality of the music, but learns to play with much less effort than where the usual method is employed.

10. If it is desired to use the instrument without the no pressure attachment it is only necessary to rotate the ring 25 until the openings 24 are closed. The shock absorbing feature may also be placed out of operation if desired.

15. For this purpose a screw 27 is inserted in the outer face of the flange 14 and is provided with an eccentric head 28 which may be rotated into position to overlap the flange 14 at 29, thus locking the tube 13 in its extended position. When the screw head 28 is in its locking position and the openings 24 are closed by the ring 25, the mouthpiece operates as the ordinary mouthpiece and has the same general appearance and is of substantially the 25 same length. It will thus be seen that the present invention embodies in one mouthpiece the ordinary form and also the shock absorbing and no pressure features.

While I have illustrated one form of the invention, it will be understood that various changes in details may be made without departing from the spirit and scope of the invention as defined in the appended claims.

I claim:—

35. 1. A mouthpiece for musical wind instruments comprising an instrument engaging member, a lip engaging member slidably mounted on said instrument engaging member, a spring interposed between said lip engaging member and instrument engaging member for protecting the lips of the user against pressure exerted on said instrument engaging member, and means for locking said instrument engaging member and lip engaging member against relative movement to render said spring ineffective and hold said lip engaging member in rigid relation with the instrument engaging member.

50. 2. A mouthpiece for musical wind instruments comprising a lip engaging member, an instrument engaging member, a spring interposed between said members for protecting the lips of the user against pressure exerted on said instrument engaging member, said members having openings therein arranged to be brought into registration for connecting the interior of said lip engaging member with atmosphere to render said instrument inoperative when excessive pressure is exerted between said members, and means for closing the passage to atmosphere formed by said openings when in registration with each other.

65. 3. A mouthpiece for musical wind instru-

ments comprising an instrument engaging member and a lip engaging member telescoping with each other, a spring interposed between said members for protecting the lips of the user against shock, means for locking 70 said members against relative movement to render said spring ineffective and hold said members in rigid relation with each other, openings in said members arranged to register with each other to form a passage to atmosphere from the interior of said lip engaging member when said members are moved to one position relative to each other, and means for closing said passage.

4. A mouthpiece for musical wind instruments comprising a pair of tubular telescoping members, a lip engaging enlargement carried at one end of one of said tubular members, an enlarged sleeve portion carried at the end of the other of said tubular members, 80 a sleeve mounted on said lip engaging portion and telescoping with said enlarged sleeve portion, and a spring interposed between said members and enclosed by the sleeve carried by said lip engaging portion.

5. A mouthpiece for musical wind instruments comprising two telescoping tubular members, an enlarged lip engaging portion mounted at the end of one of said tubular members, an outwardly projecting flange at 95 the end of the other of said tubular members, a sleeve mounted at the outer periphery of said flange, a second sleeve carried by said lip engaging member telescoping with said first named sleeve, a spring having one end 100 bearing against said lip engaging portion and the other end bearing against said flange, said spring being housed within said sleeves, and means for holding said members against relative rotation with freedom of telescoping movement.

6. A mouthpiece for musical wind instruments comprising a lip engaging portion having a tubular extension, an instrument engaging portion arranged to telescope with said extension, said instrument engaging portion and said extension having openings therethrough movable into registration with one another when a predetermined pressure is exerted upon said instrument engaging portion and said lip engaging portion, a spring 110 for normally holding said openings out of registration, means for closing the opening in said instrument engaging portion, and means for locking said lip engaging portion 120 and said instrument engaging portion against relative movement.

7. A mouthpiece for musical wind instruments comprising a lip engaging portion having a tubular extension, and an opening 125 through the wall of said extension, an instrument engaging member slidably mounted on said extension and having an opening through the wall thereof movable into registration with the opening in said extension, 130

- a slide for closing the opening in said instrument-engaging member, a spring for normally holding said openings out of registration, a sleeve enclosing said spring and having 10 means thereon for limiting the movement of said extension and instrument-engaging member in one direction, means for holding said extension and instrument-engaging member against relative rotation, and means for locking said extension and instrument-engaging member in fixed position with the openings therein out of registration.
- In testimony whereof I have signed my name to this specification on this 18th day of July, A. D. 1924.

PAUL ARTHUR.
